UNITED STATES PATENT OFFICE.

VOLNEY M. BRAFFETT, AUGUST BUSCHMANN, AND WILLIAM BUSCHMANN,
OF INDIANAPOLIS, INDIANA.

HORSESHOE.

SPECIFICATION forming part of Letters Patent No. 245,935, dated August 23, 1881.

Application filed May 10, 1881. (No model.)

To all whom it may concern:

Be it known that we, VOLNEY M. BRAFFETT, AUGUST BUSCHMANN, and WILLIAM BUSCHMANN, citizens of the United States, residing at Indianapolis, in the county of Marion and State of Indiana, have invented a new and useful Improvement in Horseshoe-Calks and Mode of Attaching them to Horseshoes, of which the following is a specification.

10 Our invention relates principally to the construction of calks for horseshoes and the mode of securing them to the shoe; and the object of our invention is to provide horseshoes with heel and toe calks which may be placed on the 15 shoe or removed therefrom without taking the shoe from the hoof. This object we accomplish by the devices illustrated in the accompanying drawings, in which—

Figure 1 represents a plan view of a horseshoe, showing the front calk screwed onto the toe and the heels prepared to receive the heel-calks. Fig. 2 is an edge view of the same. Fig. 3 represents a plan view of the shoe, showing the heel and toe calks in position. Fig. 4 is a side view of Fig. 3, and Fig. 5 is a perspective view of one of the heel-calks.

Similar letters in the various views refer to like parts.

A represents a horseshoe, with tenons B and 30 shoulders a formed at the heels.

The front calk, C, is L-shaped, the part E being provided with screw-holes, by means of which and the screws D the calk is secured to the toe of the shoe.

35 The heel-calks F are constructed similar to

that shown in Figs. 3, 4, and 5—that is, the rear end forms a head, the part f forming the calk proper, the part J forming an extension of the heels of the shoe, and is provided with a hole, K, to fit on the tenons B of the shoe. 40 The arm G projects forward, and has a hole, H', in its end, by means of which and the shoe-nail H the calk is secured on the shoe as the shoe is made fast to the hoof. When it becomes necessary to change the calks F, or to 45 remove them, the nail H is drawn out and the calk slipped off of the tenon B. The front calk, C, may be removed by removing the screws D.

What we claim as new, and desire to secure 50 by Letters Patent, is—

1. The calk F, with parts f to act as the calk proper, the part J, with hole K to receive the tenon B, and arm G, with hole H', to secure the calk to the shoe and hoof, substantially as shown and described. 55

2. The shoe A, with tenons B B at the heels, combined with the calks F, having holes K for said tenons, and arms G, with holes H' to receive a shoe-nail, H, for securing the calks to 60 the shoe, substantially as shown and described.

In testimony whereof we have signed our names to this specification in the presence of two subscribing witnesses.

VOLNEY M. BRAFFETT.
AUGUST BUSCHMANN.
WM. BUSCHMANN.
